Patented Feb. 6, 1917.

UNITED STATES PATENT OFFICE.

JERRY J. HOLECEK, OF NEW YORK, N. Y.

NECKTIE-STRETCHER.

1,215,277.

Specification of Letters Patent.

Patented Feb. 6, 1917.

Application filed August 27, 1915. Serial No. 47,638.

To all whom it may concern:

Be it known that I, JERRY J. HOLECEK, a citizen of the United States, residing at New York city, in the county of New York and State of New York, have invented new and useful Improvements in Necktie-Stretchers, of which the following is a specification.

This invention relates to stretchers especially adapted to be used for holding neckties or cravats in a stretched condition when not in use, so that when removed from the stretcher the tie will have assumed a neat and tidy and substantially flat condition, permitting the leads of the tie to hang properly when adjusted to the collar.

It is desired to provide a stretcher of this character consisting of a single piece of metal folded on itself to form relatively separable branches which constitute a stretching head, and means for holding the branches separated and the folds of the tie maintained in a stretched or tensioned condition.

It is further desired to provide a device of the above character which will be simple, inexpensive and constructed so that it is capable of being adjusted to the tie with the utmost facility.

In the drawings,

30 Figure 1 is a plan view showing the application of the stretcher to one of the leads or branches of a four-in-hand tie.

Fig. 2 is a perspective view of the lower portion of the device showing the means for holding the branches thereof in adjusted positions, relatively.

The device consists, essentially, of a single piece of relatively flat metal bent upon itself at its medial point to form a substantially arch-shaped connecting bight 1, and as illustrated, the sides thereof are twisted substantially at right angles as at 2 and then extended into relatively separable branch arms 3-3. The bight or curved connecting portion 1 is inherently of a kind or character which will permit the arms or branches 3-3 to normally lie substantially parallel to one another. The arms or branches 3-3 along their other edges, are substantially beveled or reduced so as to form substantially sharp surfaces 4 for a purpose to be hereinafter explained.

The normal form of the branches of the four-in-hand is such that the branch increases in width toward the lower end of the tie, as clearly shown in Fig. 1 of the draw-

ing, hence the present construction of the device, whereby the arms or branches 3-3 can be separated from each other to such an extent as is necessary to permit the device to conform in configuration with that of the branch of the tie with which it is associated. Further, the construction affords a means whereby the branches 3-3 may be separated to the positions shown in the drawing and the edges 4 thereof presented against the folds of the tie. In this manner the branch or lead of the tie will be stretched in a most effective manner and the tie made to assume a new, normal and presentable condition.

One of the branches 3 is reversely twisted at its free end, as at 5, and it is then extended laterally to form an arcuate branch 6 having ratchet teeth 7 on its under side. The other branch has its free terminal formed to provide a guide head 8 having a passage 9 to permit the branch 6 to freely move therethrough. The head 8 has a locking surface or tooth 10 which is designed to successively engage in the ratchet teeth, and thereby hold the arms 3-3 in such requisite positions relatively as may be essential to a proper or thorough stretching of the tie as will be understood.

In using the device the branches 3-3 are first adjusted toward each other. The device is then inserted into the tie as shown in Fig. 1, and the arms or branches 3-3 thereof are adjusted and separated from each other so as to come in close contact with the folds of the tie, pressing thereagainst under such tension as will absolutely remove from the tie all objectionable wrinkles and permit the tie to very readily assume substantially a pressed, neat and tidy condition so that it may be again made most presentable for further use.

The locking device or ratchet branch 6 through the formation of the loop or curve 5, has a normal tendency to move in the direction of the locking tooth 10. This is preferred both for the purpose of facilitating adjustment of the ratchet branch in the passage 9 and for the purpose also of causing the ratchet branch to come into positive contact with the locking surface 10 as will be understood.

From the above description taken in conjunction with the accompanying drawing, it will be seen that a tie stretcher of simple and durable structure is provided, and that the same may be easily and quickly applied

to a tie and removed from the same, and when used upon a tie, will effectively remove wrinkles from the tie and leave the same in a desired flat and smooth condition.

5. What is claimed as new is:

A stretcher comprising a single piece of flat metal bent to form a curved connecting portion, straight branches extending from said curved portion and being twisted at their points of juncture with the curved portion, and having their flat sides lying approximately at right angles to the flat sides of the said curved portion, one of said

branches having an eye located at its free end and the other branch having an extremity received in the eye and provided with teeth engageable with the eye, said extremity having its flat side lying approximately in the same planes as those in which the flat sides of the said branch portion lie. 15

In testimony whereof I affix my signature in presence of two witnesses.

JERRY J. HOLECEK.
